INVALID CHAIR

Mayo E. Roe, Elyria, Ohio, assignor to The Col-
son Corporation, Elyria, Ohio, a corporation of
Ohio

Application October 9, 1936, Serial No. 104,863

4 Claims. (Cl. 155—30)

This invention relates to invalid chairs. It is among the objects of the invention:

To provide an improved construction of invalid chair.

5 To provide an improved frame construction for invalid chairs and the like.

To provide an invalid chair having improved means to adjust the inclination of the chair back.

To provide in an invalid chair of the type com-
10 prising leg rests improved means for adjustably

positioning the same.

Other objects will be apparent to those skilled in the art to which my invention appertains.

15 My invention is fully disclosed in the follow-
ing description taken in connection with the ac-
companying drawings in which:

Fig. 1 is a side elevational view of a modifi-
cation of the invention, one of the wheels being
omitted for the sake of clearness.

20 Fig. 2 is a rear elevational view to an enlarged
scale of the embodiment of Fig. 1 with parts
broken away.

Fig. 3 is a cross-sectional view taken from the
plane 3—3 of Fig. 1.

25 Fig. 4 is a cross-sectional view taken from the
plane 4—4 of Fig. 1.

Fig. 5 is a fragmentary view to an enlarged
scale of a portion of Fig. 1.

Fig. 6 is a view looking toward the left of the
lower portion of Fig. 5.

30 Fig. 7 is a longitudinal sectional view taken
from the plane 7 of Fig. 1.

Fig. 8 is a fragmentary view of a part of Fig.
1 illustrating partly in section and partly in ele-
35 vation the subject matter of Fig. 7.

Fig. 9 is a view similar to Fig. 7 illustrating a
modification of the parts of that figure in the
position which they occupy on the other side of
the embodiment of Fig. 1.

40 Fig. 10 is a view partly in section and partly in
elevation of the subject matter of Fig. 9.

Fig. 11 is a fragmentary sectional view taken
from the plane 11—11 of Fig. 1 and drawn to a
larger scale.

45 Referring to the drawings, I have shown at
1—1 main frame members preferably formed
from tubing and comprising a forwardly and
rearwardly extending generally horizontal por-
tion 2 which in the forward portion of the chair
is bent, on a large radius of curvature upwardly
50 and forwardly in a forward portion 3 which in
the upper portions thereof is bent rearwardly
on a still larger radius of curvature, providing
an upper portion 4, and thence is bent cur-
vilinearly rearwardly and downwardly, providing a

rear portion 5 the lower end of which is sub-
stantially vertical as at 6; and the rear end of
the horizontal portion 2 is secured to the por-
tion 5 preferably by welding, this part of the
frame being preferably made from a single piece 5
of tubing.

Small rear wheels mounted in caster forks
8—8 have castering bearings 9—9 on the lower
ends of the vertical portions 6 of the frame.

The horizontal portions 2 of the frame are 10
connected by transverse frame members 10 and
11 in the rearward and forward portions thereof
respectively, these frame members preferably
also being formed from tubing and welded at
their ends to the frame member portion 2, the 15
frame member 10 being abutted at its opposite
ends upon the frame portion 2 at the weld there-
of and the frame member 11 engaging the por-
tion 2 on the underside thereof, as shown re-
spectively in Figs. 2 and 3.

20 Main or front wheels 12, having preferably
ball bearing hub structures 13—13 are rotatably
mounted on the end portions of the transverse
member 11 outwardly laterally of the frame por-
tions 2—2 as shown in Figs. 1 and 3.

25 At 14 is a seat which may be of any suitable
construction such as that well known comprising
a frame of wood or the like with a central
portion upholstered or woven from cane. The
seat has four blocks of metal 15—15 secured to
30 the underside thereof, and sheet metal supports
16—16 are welded at their lower ends to the
frame portions 2—2 and at their upper ends are
bent to provide flanges 17—17 which are secured
35 to the pieces 15—15, whereby the seat is rigidly
mounted upon and secured to the frame por-
tions 2—2.

A strip of metal 87 is secured to the underside
of the seat 14 at the rearward portion thereof
as shown in Figs. 1 and 2 and terminates in ears 40
18—18 bent upwardly and laterally spaced from
the edge of the seat.

45 A chair back 19 is provided which may be of
any suitable construction such as that suitable
for chairs of this kind and may comprise a frame
of wood or the like with a cane or upholstered
central portion. In the form illustrated the
back comprises side upright pieces 20—20 which
50 at their lower end portions have mounted there-
on channels 21—21. The lower ends of the
channels have the channel webs thereof dis-
posed between the above described ears 18—18
and the side edge of the seat 14, and the back
55 is hinged to the seat by hinge pintles 22—22.

projected through aligned perforations in the channel webs and ears 18—18.

Across the under side of the forward portion of the seat 14, is a strip of metal 23 secured to the underside of the seat and bent upward at the ends thereof adjacent the side edges of the seat to provide ears 24—24. Other strips of metal 25—25 are likewise secured to the underside of the seat, preferably superimposed upon the strip 23 and have upwardly extending ears 26—26 spaced laterally from the ears 24—24.

A frame member 27 is provided one on each side of the chair formed from bent tubing comprising a loop 28, one side of the loop extending rearwardly in a horizontal portion 29 and terminating rearwardly at 30 adjacent the back 19 and the other side of the loop being bent upward as at 31 and abutting upon and welded to the horizontal portion 29. At the intermediate portion of the loop, the tubing is flattened as at 32 and disposed between the above described ears 24 and 26 and hinged thereto by a pintle 86 extending through aligned perforations in the ears and in the flattened portion 32 of the tubing.

A sheet metal housing 33 U-shape in cross section as shown in Fig. 11 is disposed under the horizontal portion 29 of the frame member 27 being welded thereto and preferably also to the loop portion 31 of the frame member. An elongated flat tubular housing is thus provided in which a bar 34 reciprocably slides or is telescoped, one end of the bar projecting outwardly from the housing 33 and pivotally connected as at 35 to the channel member 21 on the back 19. The bar is adapted to be locked in adjusted positions longitudinally in the housing 33 to variably adjustably incline the back 19. As the back 19 pivots around the hinge connection at its lower end above described to adjust it, the frame member 27 of which the bar 34 is a part, pivots on the back at 35 and also pivots on the seat 14 at 86.

To adjustably position the bar 34 to vary the inclination of the back 19, the following means is provided. A bolt 36 is projected through the housing 33 having its head on the inner side thereof. The bar 34 has a longitudinal slot 38 therein through which the bolt 36 extends. The edges of the slot 38 are provided with pairs of opposite recesses 39—39.

A lever 40 having a handle 41 is disposed on the other side of the housing 33, the bolt 36 projecting therethrough, the bolt having a compression spring 42 thereon outwardly of which a nut 43 is provided whereby the spring 42 may hold the lever 40 against the housing. The lever has a tongue 44 projecting inwardly and adapted to be lodged in the slot 38 and in a pair of opposite recesses 39—39. By this means the tongue 44 normally locks the bar 34 against longitudinal movement. Upon depressing the handle 41 however, the tongue 44 will be withdrawn and then the bar 34 may be moved longitudinally to another position whereat the tongue 44 will snap into locking position to lock the bar to the housing.

As a modification, the form of locking device illustrated in Figs. 9 and 10 may be utilized and in some cases it may be preferred to utilize the form above described on one side, say the left side of the chair and the form now to be described in connection with Figs. 9 and 10 on the opposite side of the chair and in this latter position it will be described. A bar 34—a is provided similar to and for the same purposes as

the bar 34 and has a slot 38—a therein but instead of having the notches 39—39 has teeth 45—45 on opposite sides of the slot 38—a and aligned with each other. A clip device 46 is provided having teeth on its underside which may intermesh with the teeth 45—45 and has a prong 47 projecting into the slot 38—a. A bolt 48 is projected through the inner side of the housing and locked by a pin 37 to prevent rotation, and through the slot 38—a and through a perforation in the device 46, and outwardly thereof has a hand wheel nut 49.

By loosening the nut 49, the device 46 may be withdrawn from the tooth meshed engagement with the bar 34—a and then the bar may be adjusted longitudinally to adjust the chair back. By turning the hand nut 49 the device 46 will interlock with the bar 34—a and secure them both to the bolt 48 and therefore to the housing 33.

Arm rests preferably of wood 50 may be provided on the upper side of the frame 1, and the frame 1 therefore is bent, in the portion 4 thereof to a suitable height. The bent portions 3 of the frame 1, are disposed adjacent the outside of the knees of a patient sitting on the seat 14 whereby he is guarded from the spokes of the wheel 12.

The above described metal strips 25—25 secured to the underside of the seat 14 have bent portions 51—51 spaced below the seat 14 and with their ends generally parallel thereto. A strip of metal 88 is secured upon the under side of the seat to the strip 23 by posts 52—52 and has end portions 89—89 extending laterally beyond the posts 52—52. A pair of rectangular loops 53—53 are thus provided in the forward portion under the seat by the strip 23, and end portions 51 and 89, and posts 52. A similar pair of loops 54—54 are provided in the rearward portion of the seat by a strip 90 on the underside of the seat; a pair of Z-form pieces secured to the seat, strip 90 and having ends 55—55 spaced from the strip 90; a strip 91 secured to the strip 90 by posts 56—56 and having ends 92—92 extending laterally beyond the posts.

Rectangular board pieces 57—57 reciprocate in the loops 53 and 54 and function as supports for leg and feet rests to be described. By simply reciprocating the boards in their loops the leg rests may be adjusted forwardly and rearwardly or may be entirely withdrawn to remove the leg rests from the chair.

To the forward ends of the supports 57—57 are hinged depending leg rests 58—58 by a hinge 59. The leg rests 58 may be suitably upholstered or may comprise frames of wood or the like with cane or upholstering in the central portions thereof.

A sector 60 of sheet metal is bolted by means of a flange 61 thereof to the under side of the support 57 and has teeth 61 disposed in an arc concentric with the hinge 59.

A U-shape bracket 62 is secured by feet 63—63 thereof to the leg rest 58 on the under or inner side thereof. A shaft 64 extends through aligned perforations in the opposite legs of the U-shape bracket 62 and has a pawl 65 secured to the shaft by a set screw 66 within the bracket 62. A spring 67 surrounding the shaft 64 within the bracket 62 is anchored at one end to the shaft and at the other end to the bracket and yieldably holds the pawl 65 toward the teeth 61. The bracket 62 is braced by a pair of braces 68—68.

extending from the opposite sides of the bracket to the inner side of the leg rest 58.

The outer end of the shaft 64 is bent to provide a crank 69 terminating in a handle 70 which is generally parallel to the leg rest 58. By moving the handle 70, the shaft 64 will be rocked to remove the pawl 65 from the teeth of the sector 68 and the leg rest 58 will fall by gravity to its vertical position; or it may be lifted to an adjusted position from vertical to horizontal or higher; and then by releasing the handle 70 the pawl 65 will be engaged with a corresponding tooth and hold the leg rest in that position.

On the lower ends of the leg rests 58—58, 15 feet 71—71 are hingingly mounted as at 72, being stopped by suitable means in the position illustrated wherein they are at right angles to the leg rests 58 and being hingeable to dispose them upwardly or against the leg rests 58 in which 20 position they are out of the way when the leg rests are themselves disposed vertically whereby the chair may be used independently of the leg rests.

It is one of the advantages of my invention 25 that the several parts thereof which are to be operated are disposed convenient to the hands of an occupant of the chair. The lever handle 41, or the hand wheel 49, being within reach of the occupant's hands, his elbows when reaching these parts extending at each side behind the chair back. The frame member 2 is bent so that the arm rest 50 will be at a convenient height and so that the portion 3 thereof will be a guard 30 with respect to the wheel as above stated. The handle 70 of the leg rest adjusting means is so disposed that both it and the edge of the leg rest 58 may be grasped in the hand of the occupant and so that by squeezing them together 35 the handle 70 will be moved; and while the handle 40 70 may be out of sight of the occupant, it is easily found by guiding the hand toward it along the outer edge of the leg rest. At the same time, the adjustment parts are with equal facility 40 operable by a nurse or other attendant.

I claim:

1. In an invalid chair, a pair of laterally spaced frame elements comprising tubes each bent to provide a lower generally horizontal forwardly and rearwardly extending portion, an upwardly bent forward portion, an upper rearwardly extending arm rest supporting portion and a rearwardly depending portion, the horizontal portion secured at its rear end to the depending portion, 50 caster wheels on the lower ends of the depending portions, uprights on the horizontal portions, a seat on the uprights, front wheels supporting the

frame at the forward portion of the horizontally extending frame elements and transverse bracing elements connecting the said frame elements.

2. In an invalid chair, a transverse frame element, front wheels supporting the transverse frame element, a pair of tubular side frame elements each bent to provide a substantially horizontal forwardly and rearwardly extending portion resting at its forward end upon the said transverse frame element, and curving forwardly 10 and upwardly and then rearwardly therefrom and at its upper portion supporting an arm rest and at its rearward portion curving rearwardly and downwardly to an end below the rearward end of the horizontal portion and secured to the 15 latter and at the said end supported on a castering wheel, a seat supported on the frame elements, the forwardly and upwardly curving portions of the frame elements being disposed between the forward wheels and the legs of a chair 20 occupant sitting on the seat.

3. In an invalid chair, a pair of bar-like laterally spaced frame elements each bent to provide a lower generally forwardly and rearwardly 25 extending portion, an upwardly bent forward portion, a rearwardly extending arm rest supporting portion and a rearwardly depending portion, the forwardly and rearwardly extending portion being secured at its rear end to the depending portion, 30 caster wheels on the lower end portions of the depending portions, seat supported on the forwardly and rearwardly extending portions, front wheels supporting the frame at forward portions, and a transverse element 35 bracing the said frame elements.

4. In an invalid chair, a transverse frame element, front wheels supporting the transverse frame element, a pair of bar-like side frame elements each bent to provide a generally forwardly and rearwardly extending portion resting at its forward end portion upon the said transverse frame element, and curving forwardly and upwardly and then rearwardly therefrom and at its upper portion supporting an arm rest, and at its rearward portion curving rearwardly and 40 downwardly to an end portion below the rearward end of the forwardly and rearwardly extending portion and secured to the latter, and at the said end portion supported on a castering wheel, a seat supported on the frame elements, 45 the forwardly and upwardly curving portions of the frame elements being disposed between the forward wheels and the legs of a chair occupant sitting on the seat.

MAYO E. ROE. 55
